SLIDING CLASP FASTENER FOR FABRIC EDGES JOINING IN A CURVED LINE

Franz Schatzky, Breslau, Germany

Application April 7, 1934, Serial No. 719,509
In Germany May 6, 1932

12 Claims. (Cl. 24—205)

Sliding clasp fasteners serve for connecting parallel fabric edges and comprise fastener members arranged on the fabric edges and a slider serving for engaging and disengaging the same. The centric line of the gap between the two fabric edges may, with a certain amount of freedom of expression, be described as a line or curve (abutment line or abutment curve) along which the fabric edges abut.

Fig. 1 of the drawings show, partly in section and partly in top plan view, the two rows of fastener members of a form of construction of a sliding clasp fastener for connecting two fabric edges 1 and 2 which lie in a common plane and abut along a straight line $x-y$. 1', 1'' and 2', 2'' are the usual edge reinforcements on the two fabric edges (see also for example Fig. 1). The members of the one row fixed on the fabric edge 1 are designated by A with a subreference, for example A₁, A₂, A₃ . . . and the members of the other row on the fabric edge 2 are designated by B with a subreference, for example B₁, B₂, B₃ . . . The fastener members are provided in the usual manner with raised portions and recesses for their mutual engagement.

A perspective view of a form of construction of a fastener member is illustrated in Fig. 2. a and b are its side surfaces, c its head and d is its foot surface; e and f are its upper side edges and g and h its lower side edges.

The fabric edges do not always lie in a common plane and the abutment of the fabric edges is not always along a straight line. Sometimes the fabric edges lie in a common plane but they abut along an irregular or regular curve, in the latter instance, for example along the arc of a circle. In some cases the fabric edges lie in the wall of a cylinder or cone and abut along a cone or cylinder circle or along a spacial curve. In the case of Fig. 3, which is hereinafter described, the fabric edges 1, 2 lie for example in the same plane and their abutment line $x-y$ extends along the portion $x-z$ in an arc about the centre 3 and in the portion $z-y$ in an arc about the centre 4. In the case of the diagram shown in Fig. 5 the two fabric edges lie in the wall of a cylinder curved about the axis 5—6, whereas the abutment line $x-y$ is a plane circle, and in the case of the diagram shown in Fig. 6 the two fabric edges 1, 2 lie in the wall of a cone, the axis of which is 7—8, and which has its apex at 8'. The abutment line $x-y$ is again a plane circle.

The following expressions will be used in the description:—

“Rectilineal sliding clasp fastener” is a sliding

clasp fastener for fabric edges which lie in a plane and abut along a straight line.

“Curve sliding clasp fastener” is a sliding clasp fastener for fabric edges abutting along a curve irrespective of whether the fabric edges lie in a plane or in a curved surface.

“Plane circle sliding clasp fastener” is a sliding clasp fastener for fabric edges lying in a plane and abutting along the arc of a circle.

“Cylinder circle sliding clasp fastener” is a sliding clasp fastener for fabric edges lying in the wall of a circular cylinder and abutting along the circumference of a circle.

“Cone circle sliding clasp fastener” is a sliding clasp fastener for fabric edges lying in the wall of a cone and abutting along the circumference of a circle.

Curved sliding clasp fasteners are advantageous for many purposes, for example for overshoes for ladies and gentlemen, curtains for sleeping car windows, purses, hat boxes, tires and hoods for motor cars, protecting covers for radiators of motor cars, overcoats, for detachably connecting the fur collar or coat lining and the like.

For the connection of fabric edges abutting along a curve the known rectilineal sliding clasp fasteners were hitherto employed with the modification that the members are arranged on the outer fabric edge at a greater distance apart than on the inner fabric edge, the outer fabric edge being, however, mostly stretched or provided with incisions and the inner fabric edge drawn together or overlapped. Consequently when the fabric edges abutting along a curve are interconnected by a rectilineal sliding clasp fastener, the members only interlock imperfectly, and the more imperfect the sharper the curve is. Moreover, the slider which is the case of rectilineal sliding clasp fasteners is usually rigid and symmetrical relative to its longitudinal axis, tends to force the members out of the path, when the rectilineal fastener is employed for connecting fabric edges abutting along a curve, with the result that the sliding clasp is heavily stressed and a relatively strong effort is required to slide it.

The curve sliding clasp fastener according to the invention overcomes this objection in that it possesses parts which are constructed to conform with the curvature of the abutment curve.

Several embodiments of the invention are illustrated by way of example in the accompanying drawings in which:—

Fig. 1 shows a rectilineal fastener partly in top

plan view and partly in horizontal longitudinal section.

Fig. 2 is a perspective view of one form of construction of a fastener member of a rectilinear sliding clasp fastener.

Fig. 3 is a top plan view of a plane curve fastener for an abutment curve with varying curvature.

Fig. 4 is a cross-section on line 4-4 of Fig. 3.

Fig. 5 is a diagrammatic view for explaining the spacial position of the fabric edges for a cylinder circle fastener.

Fig. 6 is a diagrammatic view for explaining the spacial position of the fabric edges for a cone circle fastener.

Figs. 7 to 9 are diagrammatical views on a considerably enlarged scale, showing a perspective view of a plane circle sliding clasp fastener, a cylinder circle sliding clasp fastener and a cone circle sliding clasp fastener respectively.

Fig. 10 is a vertical section on line 10-10 of Fig. 12 through a slider for a curve sliding clasp fastener with varying curvature.

Fig. 11 is a horizontal section through the slider taken on line 11-11 of Fig. 10.

Fig. 12 is a cross-section through the slider on line 12-12 of Fig. 11.

Fig. 10a shows a top plan view of the modification of the slider for a curved sliding clasp fastener with varying curvature.

Fig. 11a is a vertical section through the slider on line 11a-11a of Fig. 10a.

Fig. 12a is a cross section through the slider on line 12a-12a of Fig. 10a.

Fig. 13 is a section on line 13-13 of Fig. 14 through a slider for a plane circle sliding clasp fastener of the type shown in Fig. 7.

Fig. 14 is a horizontal section through the slider taken on line 14-14 of Fig. 13.

Fig. 15 is a cross section through the slider taken on line 15-15 of Fig. 14.

Fig. 16 is a longitudinal section on line 16-16 of Fig. 17 through a slider for a cylinder circle sliding clasp fastener of the type shown in Fig. 8.

Fig. 17 is a top plan view of the slider.

Fig. 18 is a perspective view of a slider for the cone circle sliding clasp fastener shown in Fig. 9 with partly cut away front wall and left end cut off on line 18-18 of Fig. 19.

Fig. 19 is a top plan view of the slider.

Fig. 20 is a medium longitudinal section through the slider on plane 20-20 of Fig. 19 in developed state.

In Figs. 3 and 7 to 9 as in Fig. 1 the two fabric edges are designated by 1 and 2 and the members by A₁, A₂, A₃ . . . and B₁, B₂, B₃ . . . respectively whereas x-y (see Fig. 3) is the curve along which the fabric edges 1, 2 abut.

The new shape of the fastener members according to the invention can be seen from the considerably enlarged perspective view shown in Fig. 7. If x'-y' is a small portion of the abutment curve x-y, this curve portion x'-y' will have a certain curvature centre m. If the curve portion x'-y' is short enough it can be regarded as a straight line and a plane can be imagined through it and the centre m, which plane is the curvature plane of the curve at the point in question. If a vertical line S-S is imagined erected on this plane in the centre of curvature m, the planes of the two side surfaces (a and b in Fig. 2) of the fastener members coordinated to the corresponding curve portion in question will, according to the invention join in this line s-s.

The conditions are particularly simple when

the fabric edges lie in one plane along their entire length and their abutment curve forms an arc of a circle. Thus, for example in the case of Fig. 3, the abutment curve lies in the plane of the drawings, and the projections of the side surfaces a, b of the members on to the plane of the drawings extend in the actual direction of the radius of the circle, which means that these projections converge, as far as the members coordinated to the arc x-z are concerned, towards the centre 3 and, as far as the members coordinated to the arc z-y are concerned, towards the centre 4. Consequently, the members A and B (Fig. 3) coordinated to the arc x-z taper in the direction of the arrow I and the members A and B coordinated to the arc z-y taper in the direction of the arrow II. Herefrom follows, that in the case of sliding clasp fasteners for fabric edges which lie in one plane and abut along a curve with varying curvature, the members A fixed on the fabric edge 1, (and the same applies also for the members B fixed on the fabric edge 2) are of different shape, whereas in the case of plane circle sliding clasp fasteners all the members A fixed on the fabric edge 1 (and also all the members B fixed on the fabric edge 2) are of uniform shape. In both instances, however, the members A are different from the members B.

Fig. 8 shows on a considerably enlarged scale the cross section through a cylinder circle sliding clasp fastener, in which the fabric edges lying according to Fig. 5 in the wall of a cylinder abut along the arc x-y of a circle. In the case of a plane circle sliding clasp fastener, as shown in Fig. 7, the projections of the side edges e-f on the one hand and g-h (see Fig. 2) on the other hand of each member converge in the line s-s; compared herewith all the edges e, f, g, and h in the form of construction shown in Fig. 8 are parallel to one another and to the cylinder axis 5-6 (Fig. 8). Also in this instance all the members A and also all the members B are uniform, whereas the members A are the negative of the members B and consequently different therefrom.

Fig. 9 shows a considerably enlarged perspective view of a cross section through a cone circle sliding clasp fastener. Again the projections of the two side surfaces a and b of each member converge, in this instance towards the axis 7-8. Further the surfaces c and d also taper in the direction towards the apex of the cone, as the projections of the side edges e and f of all members converge towards the common cone apex 8' (respectively the projections of the edges g and h towards the cone apex 8''). In this instance all the members A are again different from the members B, but all the members A are alike and all the members B are alike.

Figs. 10 to 17 show different forms of construction of the fastener slides. In all the figures 9 designates the head plate, 10 the foot plate of the slider, 11 its web connecting the two plates on one end, 12 the handle serving for shifting the slider and 15 its guide wedge.

If both fabric edges 1 and 2 lie in one plane along their entire length, the abutment curve is however not regular but irregularly curved and changes its direction, a slider such as illustrated in Figs. 10 to 12 is preferably used. In this slider the side walls are formed by blade springs 13 which are fixed in suitable manner on the bent edge extensions 14 of the two slider plates 9, 10 and leave free between them the gap necessary for the passage of the fabric edges. The guide

wedge 15 arranged between the two slider plates is not rigidly connected with the plates but is movable relatively thereto, so that it can shift in lateral direction. In the example illustrated the 5 guide wedge 15 is carried by two arms 16 an upper arm and a lower arm, these two arms 16 being each connected with the two slider plates 9 and 10 by a pin 17 arranged in the same axial plane and serving as pivot axle. The arrangement may, 10 however, be such, as shown in Figs. 10a to 12a that the guide wedge 15 carries on its upper end and on its lower end a pin-shaped extension 19, and the two pin-shaped extensions each engage in a guide slot 20 in the corresponding 15 slider plates 9, 10, these slots being curved in an arc around an imaginary axis 17' corresponding to the axis of the two pins 17 of the slider shown in Figs. 10 to 12. In such a construction, as well that shown in Figs. 10 to 12 as that shown 20 in Figs. 10a to 12a, the fastener slider can fit snugly to the curved path of the two rows of members of the sliding clasp fastener.

Figs. 13 to 15 show a slider for a plane circle sliding clasp fastener. The slider corresponds to 25 the rigid slider generally employed for rectilinear sliding clasp fasteners only with the difference that its longitudinal axis n—n is curved in the same arc as the abutment curve of the two fabric edges. The side walls 18 of the slider are formed 30 by bent edge portions of the two slider plates 9, 10. The guide wedge 15 is rigidly connected with these plates.

Figs. 16 and 17 show a rigid slider for a cylinder circle sliding clasp fastener. In this case 35 the two slider plates 9, 10 are bent to cylinder surfaces concentric to the cylinder surface of the fabric edges. 18 are the rigid side walls of the slider.

For a cone circle sliding clasp fastener the slider 40 shown in Figs. 10 to 12 with elastic side walls and a guide cone freely movable from the medium position towards the one or other longitudinal side of the slider may be employed. For a cone circle clasp fastener in which the cloth 45 edges meet along a circle a rigid slider as shown in Figs. 18 to 20 may be employed. In this instance similar to Fig. 17 the two plates 9, 10 are curved, the curves corresponding, however, this time to conical surfaces which are concentric to 50 the conical surface of the cloth edges. When flatly spread out in a plane, the two plates, as shown in Fig. 20, possess a shape similar to that shown in Fig. 14; the radius of the circle, according to which the middle line n—n of the corresponding slider plate is curved, then corresponds to the generatrix (side length) of that cone, according to which this slider plate is bent 55 and the base circle of which is the cone circle coinciding with the line n—n.

60 I claim:—

1. A sliding clasp fastener comprising fabric edges abutting along a curve with definite large curvature radius, fastener members fixed on the fabric edges, and a slider adapted to interlock and disengage said members, the planes of the two side surfaces of each fastener member extending transversely to the fabric edges converging in wedge shape towards the vertical line standing on its curvature plane in the centre of 65 the curvature.

2. A sliding clasp fastener comprising fabric edges abutting along a curve with definite large curvature radius fastener members fixed on the fabric edges, and a slider adapted to interlock and disengage said members, said slider hav-

ing elastic side walls and a guide wedge freely movable in the medium position towards the one or other longitudinal side wall.

3. A sliding clasp fastener comprising fabric edges abutting along a curve with definite large 5 curvature radius, fastener members fixed on the fabric edges, and a slider adapted to interlock and disengage said members, the planes of the two side surfaces of each fastener member extending transversely to the fabric edges converging 10 in wedge shape towards the vertical line standing on its curvature plane in the centre of the curvature, and said slider having elastic longitudinal side walls and a guide wedge freely movable in the medium position towards the 15 one or other longitudinal side wall.

4. In a sliding clasp fastener, fabric edges abutting along a curve with definite large curvature radius, fastener members fixed on the fabric edges and a slider adapted to interlock and disengage 20 said members, said slider comprising elastic side walls and a guide wedge freely movable in the medium position towards the one or other longitudinal side wall.

5. A sliding clasp fastener comprising fabric 25 edges situated in a plane and abutting along a circle, fastener members fixed on the fabric edges, and a slider adapted to interlock and disengage said members, the planes of both the side surfaces of each of the fastener members, extending transversely to the fabric edges, converging towards 30 a vertical line standing on the plane of the fabric edges in the centre of the circle.

6. A sliding clasp fastener comprising fabric edges situated in a plane and abutting along a 35 circle, fastener members fixed on the fabric edges, and a slider adapted to interlock and disengage said members, said slider being rigid and having a longitudinal axis extending along the circle along which the two fabric edges abut.

7. A sliding clasp fastener comprising fabric edges situated in a plane and abutting along a circle, fastener members fixed on the fabric edges, and a slider adapted to interlock and disengage 40 said members, the planes of the two side surfaces of each of the members which stand transversely to the fabric edges converging towards a vertical line standing on the plane of the fabric edges in the centre of the circle, said slider being rigid and having a longitudinal axis extending 45 along the circle along which the two fabric edges abut.

8. A sliding clasp fastener comprising fabric edges situated in the wall of a circular cylinder and abutting along a circle, fastener members fixed on the fabric edges, and a slider adapted to interlock and disengage 50 said members, the planes of the two side surfaces of each member which stand transversely to the fabric edges converging towards the axis of the cylinder.

9. A sliding clasp fastener comprising fabric edges situated in the wall of a circular cylinder and abutting along a circle, fastener members fixed on the fabric edges, and a slider adapted to interlock and disengage 55 said members, the planes of both the side surfaces of each member which stand transversely to the two fabric edges converging towards the cylinder axis, and said slider being rigid and having a head plate and a foot plate curved according to cylinder surfaces 60 concentric to the cylinder surface of the fabric edges.

10. A sliding clasp fastener comprising fabric edges situated in the wall of a cone and abutting 65 in a circle, fastener members fixed on the fabric 70 edges.

edges, and a slider adapted to interlock and dis-
engage said members, the planes of both the
side surfaces of each of said members, which
stand transversely to the fabric edges, converging
5 towards the cone axis, and the side edges of each
of said members converging in the apex of a cone.

11. A sliding clasp fastener comprising fabric
edges situated in the wall of a cone and abutting
in a circle, fastener members fixed on the fabric
10 edges, and a slider adapted to interlock and dis-
engage said members, said slider having a head
plate and a foot plate bent according to conical
surfaces concentric to the cone surface of the
fabric edges and possessing in developed flat state
15 a longitudinal axis curved according to a circle.

12. A sliding clasp fastener comprising fabric
edges situated in the wall of a cone and abutting
in a circle, fastener members fixed on the fabric
edges, and a slider adapted to interlock and dis-
engage said members, the planes of both the side 5
surfaces of each member, which stand transverse-
ly to the fabric edges, converging towards the
cone axis and the side edges of each member con-
verging in the apex of a cone, said slider having
a head plate and a foot plate bent according to 10
form conical surfaces concentric to the conical
surface of the fabric edges, and possessing in flat
developed state a longitudinal axis curved ac-
cording to a circle.

FRANZ SCHATZKY. 16
